UNITED STATES PATENT OFFICE.

WILLIAM T. WATERSTRAAT, OF CHICAGO, ILLINOIS.

SWINGING DOOR.

No. 906,175.

Specification of Letters Patent.

Patented Dec. 8, 1908.

Application filed May 13, 1907. Serial No. 373,278.

To all whom it may concern:

Be it known that I, WILLIAM T. WATERSTRAAT, a citizen of the United States, residing at Chicago, in the county of Cook and State of Illinois, have invented a new and useful Improvement in Swinging Doors, of which the following is a specification.

My invention relates to improvements in revolving doors of the class exemplified in United States Letters Patent, No. 836,843, dated November 27, 1906, to T. Van Kamme.

The variety of revolving door referred to involves vertical wings on a pivot centrally located in a casing within a door-way to prevent draft and to permit passage through the door-way without opening the door to the access of wind and dust, the casing comprising opposite segments between which the wings 20 ft; and the wings are usually adapted to be folded together to collapse them in warm weather and in cases of emergency and thus leave open passages at their opposite sides for permitting rapid ingress or egress through the door-way.

The object of my invention is to provide improved means for releasably bracing the wings in their unfolded operating condition.

In the accompanying drawings, Figure 1 shows a revolving door provided with my improvement by a view in sectional elevation with one of the wing-braces represented in hanging position by dotted lines, the section being taken at line 1 on Fig. 2 and regarded in the direction of the arrow; Fig. 2 is a section taken at the line 2 on Fig. 1 and viewed in the direction of the arrow, showing the wings braced by my improved means and equipped on their vertical edges with weather-stripping; Fig. 3, a plan view showing the wings, removed from the casing, in their folded or collapsed condition, and equipped with my improved bracing means; Fig. 4, a broken, enlarged section taken at the line 4 on Fig. 1 and viewed in the direction of the arrow; Fig. 5, a view in elevation of the hinge-bar for the door-wing braces; Fig. 6, an enlarged section taken at the line 6 on Fig. 1 and viewed in the direction of the arrow 50 showing the construction of the weather-stripping as provided on the edges of the wings; Fig. 7, an enlarged section taken at the line 7 on Fig. 1 and viewed in the direction of the arrow, showing the construction of the weather-stripping as applied to the upper edges of the door-wings, and Fig. 8, an

enlarged section taken at the line 8 on Fig. 1 and viewed in the direction of the arrow, showing the construction of the weather-stripping as applied to the lower edges of the wings.

A door-casing of a usual construction having arc-shaped side-walls 10 flanking the door-opening 11, is represented at 9 and in this door-opening a revolving door 12 is supported. As represented the door 12 comprises wings 13, 14, 15 and 16, preferably four in number as shown, arranged to be held, when in their extended position, at right-angles to each other. The wings 14 and 15 are hinged together at their adjacent vertical edges, as indicated at 17, and the wings 13 and 16 are similarly connected together, as represented at 18. The wings 13 and 15 are rigidly and permanently secured together in alining or substantially alining relation by a bar 19 securely fastened near its opposite ends to the opposite sides of these wings, as by screws (not shown) passing through screw-holes 20 into the wings. This bar, as more clearly illustrated in Fig. 5, has a central thickened portion 21 containing a vertical opening through which the shaft 22 forming a pivot for the door, extends. Provided on the bar at opposite ends are lugs 23 each having a horizontal opening 24 through it, and in the bar adjacent to each lug and the opposite ends of its thickened portion 21, openings 25 are formed. For supplementing the bar 19 in maintaining the wings in releasably extended braced condition and thereby to aid in strengthening the structure, flat metal braces 26, of general triangular shape and with convexly curved outer edges, are provided between the pairs of wings 13, 14 and 15, 16 respectively, each brace having preferably two spaced bearing-lugs 27, which extend into the corresponding openings in the bar 19, the braces being pivoted to the bar at its opposite ends to adapt them to extend in opposite directions between the corresponding wings, by rods 19¹ insertible through the lugs 23, bearing-lugs 27 and into the adjacent ends of the bar-portion 21. The free ends of the braces are thus adapted to be raised and lowered on the bar 19 as a hinge, and when raised to the horizontal position illustrated in Fig. 2, may be releasably fastened in place to the adjacent wings, for rigidly holding them in their properly spaced relation with reference to the doors carrying the braces, by any suit-

able means. The means for the purpose shown consist of headed studs 14¹ and 16¹ projecting laterally from the wings 14 and 16, respectively, into position to be engaged by corresponding sockets 26¹ formed in the under sides of the braces near their outer ends, when the braces are lowered into operative position.

The permanent bar-connection between the wings 13 and 15 serves to hold them rigidly in the alining relation referred to, regardless of the pressure which may be exerted against them when the door is operated, and the braces 26, when the wings are unfolded, serve rigidly to maintain the wings 14 and 16 in the desired spaced relation to the wings 13 and 15. Thus by the use of only two braces, each wing is so rigidly braced that when the door is operated there will be no yielding of the wing pressed against, and, furthermore, continued operation of the door will not strain the brace-connections and impair the door structure.

When it is desired to unfold the wings to afford unobstructed passage-ways through the door-way, the braces 26 are turned on their hinges to the depending position represented by dotted lines in Fig. 1, and the wings 14 and 16 are then turned on their hinge-connections to the positions indicated in Fig. 3, thereby folding the braces between the wings and freeing the sides of the door of obstructions against free passage through the door-way. The flat shape of the braces prevents them from obstructing flat folding of the wings, and their curved outer edges avoid their projecting into the path of persons passing through the door-way by turning the wings.

As shown in the drawings, each wing is provided on its outer edge, top and bottom, with weather-stripping for engaging, respectively, with the top, bottom and sides of the casing 9. The weather-stripping for the outer vertical edges of each wing, which is provided to be laterally adjustable thereon, to take up wear, comprises a strip 28 of flexible material, such as rubber, or the like, extending the full length of the edge of the wing to which it is applied, and having a contact-strip 29 of felt, or the like, fastened on its outer-edge portion. The strip 28 is confined at its inner edge, where it is beaded as shown at 30, in a vertical recess 31 of rectangular cross-section in the edge of the wing, by a strip 32 having a longitudinal recess 33 into which the bead 30 projects, and provided with transverse slots 34 through which screws 35 for clamping the rubber strip 28 between the wing-edge and the strip 32, extend. The strip 32 contains a longitudinal groove 36 along its inner edge which receives a bead 37 on a housing strip 38 releasably secured to the wing, as by screws 39, 65 and bearing at one edge against the rubber

strip 28 and at its opposite shouldered edge against the wing-proper. Thus, if from wear or otherwise, it is desired to change the position of the weather-stripping on the wing, such adjustment may be readily effected by first removing the housing 38 and then loosening the screws 35 thereby permitting the strip 28 to be moved to the desired position. When the adjustment is effected the screws 35 may again be tightened and the housing replaced.

The construction of weather-stripping shown for the top edge of each wing is as follows: Confined between the wing-proper and a strip 40 secured to the wing along its upper-edge portion, are spiral springs 41 the free ends of which normally extend upwardly and bear against the under side of an angle-strip 42, whose sides form a seat for a strip 43, preferably of rubber, having its outer edge of curved shape in cross-section. Secured to extend over the top of the strip 40 and over the hinges 41, plate 42 and strip 43, to which latter it is secured, as by tacks 45, is a strip 44 of felt, or the like, which extends the entire length of the top edge of the wing. Thus these felt strips, by reason of the spring construction provided, are constantly pressed against the top of the door-casing, and any wear on the felt is compensated for by the springs.

The weather-stripping for the lower edges of the wings is similar to that just described for the top edges, excepting that in place of the strips 40, 43 and 44, a depending strip 46 of rubber, or the like, confined between the depending flange of the angle-bar 42 and a strip 47 seated on the horizontal flange of the bar, is provided. Thus wear upon the contact-edge of the strip 46 is compensated for in the manner before described.

By providing the bar-connection between the wings 13 and 15, provision of but two cross-braces is required, thereby simplifying the construction and dispensing with those parts which, when the door-wings are folded, would be in the way of persons using the resultant passage-ways.

The provision of the weather-stripping as described insures a close fit of the door within its casing at all points, thereby effectively barring draft through the door-way and the ingress of wind and dust.

What I claim as new and desire to secure by Letters Patent is:

1. A four-winged revolving door having a bar rigidly connecting two of the wings in substantial alinement with each other, and the other two wings hingedly connected with them, and braces hingedly supported on said bar to adapt them to be lowered on their hinges to permit folding the wings and to be extended into engagement with the hinged wings for securing them in their position of closure.

2. A four-winged revolving door having a bar rigidly connecting two of the wings in substantial alinement with each other, and the other two wings hingedly supported to adapt 5 them to be swung independently of each other, said bar having lugs and openings, rods supported in said lugs, and braces having projections at which they are journaled on said rods at the openings in the bar to

adapt them to be lowered to permit folding 10 the hinged wings and to be extended into engagement with the other wings for securing the four wings in their position of closure.

WILLIAM T. WATERSTRAAT.
